UNITED STATES PATENT OFFICE.

WILLIAM H. PARKS, JR., OF MARYSVILLE, CALIFORNIA.

STEERING MECHANISM FOR HEADERS AND THRASHERS.

SPECIFICATION forming part of Letters Patent No. 319,117, dated June 2, 1885.

Application filed July 26, 1884. (No model.)

To all whom it may concern:

Be it known that I, WILLIAM H. PARKS, Jr., of Marysville, county of Yuba, and State of California, have invented an Improvement 5 in Steering Combined Headers and Thrashers; and I hereby declare the following to be a full, clear, and exact description thereof.

My invention relates to a new and useful improvement or method for steering combined headers and thrashers; and it consists 10 in such an arrangement of levers, pulleys, and ropes by which the operator is enabled to stand in the most convenient position for seeing his work ahead, and from which he is 15 enabled through the ropes to operate the steering-wheel.

The object of my invention is to enable the steerer to locate himself in such a position 20 that his view of the field in front will not be obstructed by the intervening machine, and at the same time give him the necessary means by which he can govern the steering-wheel. In machines of this class the thrasher portion is usually so cumbersome as to entirely cut off from view of the steerer the 25 work ahead, and he is under the necessity of guiding his machine by signals given by other persons. This is a great disadvantage, and by overcoming this and giving him an opportunity to see where his machine is traveling a useful and convenient result is produced.

My present invention contemplates the location of the steerer upon the platform of the 35 header portion of the machine, in which position he is at one side of the thrasher portion, and can see through the header portion, which is generally of such light frame-work as not to obstruct his vision.

Referring to the accompanying drawings 40 for a more complete explanation of my invention, Figure 1 is a plan of my device for steering a combined header and thrasher. Fig. 2 is a side view.

The machine consists, generally, of a thrasher portion, A, which may be supposed to have 45 the usual parts, and the header portion B, of which C is the usual platform at the back of the header.

D is the push-beam, carrying the usual double-trees, E, and single-trees F, to which the horses are hitched by which the machine is advanced.

G is the swiveling steering-wheel, near the rear end of the push-beam. Up on top of the 50 spindle or stem g of this wheel is a lever, H. Upon the platform C of the header portion, near one side, is a vertical shaft, I, mounted in such a manner as to be rotated in its bearings. Upon the top of this shaft is a lever, i, 55 to the center of which is attached the operating-lever J. Upon the push-beam D, between the steering-wheel and the platform, is a standard, K, on top of which is a cross-piece, l, upon each end of which are mounted in a 60 horizontal plane the pulleys L.

M are ropes attached at their rear ends to the ends of the lever H on top of the standard g of the steering-wheel. These ropes thence extend forward, passing around pulleys L, and are secured at their forward ends to each end of the lever i on top of the oscillating shaft I on the header-platform C. The steerer stands upon the platform C, and by operating-lever J pulls upon either of ropes 65 M, through which the power is transmitted to the lever H, by which the steering-wheel G is turned, and thus the entire machine is guided. From his position on the platform he can readily see ahead, and can judge of 70 where his machine is going.

I do not claim the mere transmission of power to the steering-wheel by means of ropes or chains, as such have long been used in boats and ships; but I conceive my invention 75 consists in the arrangement of parts herein shown and described, and their application to the machine, by which useful and advantageous results are produced.

Having thus described my invention, what 80 I claim as new, and desire to secure by Letters Patent, is—

In combination with the push-beam D of a 85 combined header and thrasher, and the steering-wheel G, having spindle g, a means by which said spindle is oscillated to operate the steering-wheel, consisting of a lever, H, upon the top of the spindle, the pulleys L upon a

suitable standard secured to the push-beam, the oscillating shaft I on the platform of the header portion of the machine, having lever *i* upon its top, the operating-lever J, connected with said lever *i*, and the cords or ropes M, connected with lever H, passing around pulleys L and connected with lever *i*, substantially as and for the purpose herein described.

In witness whereof I have hereunto set my hand.

WILLIAM H. PARKS, JR.
